UNITED STATES PATENT OFFICE.

JOSEPH L. WOHLMAN, OF HARTINGTON, NEBRASKA.

WHIP-SOCKET.

1,176,330.

Specification of Letters Patent. Patented Mar. 21, 1916.

Application filed June 24, 1915. Serial No. 36,000.

To all whom it may concern:

Be it known that I, JOSEPH L. WOHLMAN, a citizen of the United States, residing at Hartington, in the county of Cedar and State of Nebraska, have invented certain new and useful Improvements in Whip-Sockets, of which the following is a specification.

The present invention relates to a detachable whip socket, and has for its object to provide a device of this character which embodies novel features of construction whereby it can be quickly applied to any wagon or piece of farm machinery in any convenient location.

Further objects of the invention are to provide a device of this character which is comparatively simple and inexpensive in its construction, which can be formed from a single piece of sheet material, which can be quickly placed in position or removed therefrom, and which can be used interchangeably upon a number of vehicles, being susceptible of application to each of them in the particular position most convenient to the driver.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:

Figure 1 is a front elevation of a whip socket constructed in accordance with the invention. Fig. 2 is a rear elevation thereof. Fig. 3 is a horizontal sectional view taken on the line 3-3 of Fig. 4. Fig. 4 is a transverse sectional view taken on the line 4-4 of Fig. 1, showing the whip socket in position on a dashboard or the like.

Corresponding and like parts are referred to in the following description and indicated in all the views of the drawings by the same reference characters.

Specifically describing the present embodiment of the invention, the reference character A designates the body portion of the whip socket, and B a clamping arm which is integral with the body portion, both the body portion and clamping arm being adapted to be inexpensively manu-

factured from a single piece of sheet material.

The body portion A includes a substantially flat back 1 having an integral wing at one side thereof which is curved forwardly and rearwardly to provide the front 2 of the body portion and has the edge thereof connected to the opposite side of the back by a suitable seam 3. In a somewhat similar manner the bottom of the socket is formed by an integral wing 4 which is bent upwardly and secured to the front portion 2 of the socket. The back 1 may have a pair of parallel ribs 5 pressed rearwardly therefrom, said ribs extending longitudinally of the socket of the body portion and serving both to reinforce the back thereof and to admit of the socket obtaining a firm bearing against the dashboard or other member upon which it may be clamped.

The clamping arm B is formed by an integral extension at the upper end of the back 1, said extension being returned so that the body portion of the clamping arm is disposed in a plane spaced from and parallel to that of the back 1. The end of the clamping arm is bifurcated to provide diverging fingers 6 which project downwardly at an angle to each other and extend laterally on opposite sides of the socket A. Clamping screws 7 are threaded in the clamping arm B at the upper end thereof and also in each of the diverging fingers 6. These three clamping screws can be easily manipulated by the fingers and admit of the device being readily clamped in position upon the dashboard of a vehicle or in any convenient position upon a piece of farm machinery or the like.

The rearwardly projecting ribs 5 at the back of the socket or body portion A obtain a firm bearing upon the front of the dashboard or like member to which the device is applied, while the three clamping screws 7 engage the opposite side of the dashboard to retain the device rigidly in position. The diverging fingers 6 at the lower end of the clamping arm B coöperate with the ribs 5 at the back of the socket A to retain the device rigidly in position and prevent the same from wabbling or working from side to side. In order to remove the device it is merely necessary to loosen the three clamping screws 7 and to then lift it from position. The whip socket can be used interchangeably upon different

vehicles and various pieces of farm machinery, and in each instance can be placed in that particular position most convenient to the driver.

Having thus described the invention, what I claim as new and desire to secure by Letters Patent, is:—

A device of the character described, including a socket and clamping arm formed 10 from a single blank of sheet material, the socket having a substantially flat back plate formed with an integral side wing which is returned to form the front of the socket and also formed with an integral bottom wing 15 which is bent upwardly to form the bottom of the socket, a pair of longitudinally extending bearing ribs being pressed rear-

wardly from the back plate and the clamping arm being formed by a returned integral extension at the upper end of the back plate, the body portion of the clamping arm occupying a spaced and parallel relation to the back plate and the end thereof being bifurcated to form diverging fingers which project laterally upon opposite sides of the 20 socket, and clamping screws threaded upon the clamping arm and diverging fingers. 25

In testimony whereof I affix my signature in the presence of two witnesses.

JOSEPH L. WOHLMAN.
